UNITED STATES PATENT OFFICE.

CARL PHARIS, OF NEWARK, OHIO, ASSIGNOR TO THE WESTERN AUTO SUPPLY COMPANY, A CORPORATION OF CALIFORNIA.

DESIGN FOR A TIRE.

Application filed March 20, 1922. Serial No. 1,264. Term of patent 14 years.

To all whom it may concern:

Be it known that I, CARL PHARIS, a citizen of the United States, residing at Newark, in the county of Licking and State of Ohio, have invented a new, original, and ornamental Design for Tires, of which the following is a specification, reference being had to the accompanying drawing, forming part

thereto.

Figure 1 is a fragmentary top plan view of a tire, showing my new design, and

Figure 2 is a cross sectional view of the tire.

I claim:

The ornamental design for a tire, as shown.

CARL PHARIS.
